LABEL FOR STUDENTS' UNKNOWN ANALYSIS SAMPLE PACKAGES

Harold A. Fales, Leonia, N. J., assignor to
The Fales Chemical Company, Incorporated,
Cornwall Landing, N. Y., a corporation of New
York

Application June 14, 1929, Serial No. 379,839

1 Claim. (Cl. 35—12)

This invention relates to students' "unknown" analysis sample packages, and aims to provide improvements therein.

In courses of analytical chemistry, students are given a sample for analysis, the sample usually containing a mixture of different compounds, all of which compounds are unknown to him, and he is given the problem of making an analysis and reporting the various compounds and the amounts 10 thereof contained in the sample. These samples are commonly referred to as "unknowns".

The preparation of these samples requires considerable labor and time on the part of the teacher. Furthermore, there is considerable opportunity for mistakes being made in the samples given out to students, in the usual practice which is followed in the preparation and packaging of these samples. It is of course of the highest importance that the teacher have the greatest confidence in the true analysis of the "unknown" 20 which is given to each student.

The present invention provides a package which contributes greatly to the convenience of teachers of analytical chemistry, which admits of exact 25 knowledge on the part of the teacher of the contents of the "unknown", and of innocence of the student as to the contents of the materials to be determined by his analysis of the "unknown".

The invention furthermore provides a package 30 particularly adaptable to the preparation and distribution of samples of "unknowns" on a large scale.

An embodiment of the invention is illustrated 35 in the accompanying drawing, wherein:

Figure 1 is a view in elevation of a package.

Fig. 2 is a development of the view, Fig. 1, in order to more clearly show the structure.

Fig. 3 is a detail face view of the label which underlies the label shown in Figs. 1 and 2.

Fig. 4 is a perspective view showing the detachable label partly detached.

Referring to said drawing, numeral 10 designates a container, here shown in form of a small wide-mouthed vial, and in which a substance to be analyzed, usually in the form of a powder, and commonly known as an "unknown", is placed. The "unknown" usually consists of a mixture of metal compounds, and different bottles are filled with different samples or "unknowns", the number 45 of "unknowns" used in a class usually being such as will avoid the likelihood of two students in a class knowingly working upon the same "unknown".

Means are provided for identifying each package (without reference to its contents), and such

means is ordinarily in the form of a serial number, as indicated at 12, Fig. 3. The serial number is most conveniently applied to the package by printing it or writing it on a label 14, which label 14 is securely attached to the container or vial, 60 as by means of a suitable adhesive.

The label 14 may also bear other matter, as for example a line or space 16 on which the student can put the date and initials showing when he received the sample. The label 14 should be 65 otherwise free of any matter which would convey to the student any knowledge of the contents which he is to find by analysis. The label 14 and the serial number thereon simply provides a means for identifying the student with a particu- 70 lar package.

Means are also provided for disclosing the analysis of the contents of the container, and which may be readily removed by the teacher, prior to handing out the package or container to the student. This means is preferably in the form of a label 20.

The label 20 is provided with one or more tabs 22, which tab or tabs are attached to the container 10, preferably by means of a suitable adhesive. 80 The label 20 is attached to the container through the tabs 22, the tabs accordingly providing a readily severable connecting means between the label and container, whereby the label 20 may be bodily removed upon severance thereof from 85 the tab or tabs 22.

The severance of the label 22 from the tab or tabs 22 may be facilitated by providing a line of perforations 24 between the label 20 and the tab or tabs. When a label 14 is used, and both 90 labels are used upon a small vial, the label 20 is conveniently placed over the label 14, the tab or tabs 22 being connected to the vial at the sides of the said label 14.

The label 20 is provided with means disclosing 95 the analysis of the contents of the said container, as shown at 26. These means are conveniently in the form of a numeral, which numeral corresponds with a complete analysis on a list made up or supplied by the maker of the package. 100 The full analysis, instead of a key number could of course be printed or written upon the label 20.

The label 20 is also provided with an identifying 105 package number, as indicated at 28. The package number on the label 20, indicated at 28 corresponds to the package number on the container 10 or under label 14, the identifying package number in this instance being "127".

The label 20 may also bear a line or space 30 on which the teacher may place the date when 110

the sample is given out to a student, and it may also bear a line or space 32 on which the teacher may place the name of the student to whom the particular package or sample is given.

5 A string 34 is preferably provided for facilitating the severance of the label 20. In order to prevent the string 34 from becoming detached and lost, the said string 34 is preferably in the form of a double thread which is stitched through 10 the label by means of a sewing machine, through the material of which the label is made (usually paper) between the label and a tab (or tabs). The stitch is preferably a lock stitch, whereby 15 the two threads are locked through the paper, and cannot be separated from the paper by pulling thereon, except by severing the label from the tab.

20 A moisture-proof seal 35 is preferably provided over the mouth of the vial, the seal being conveniently a cellulose-base material. This seal also provides a means of preventing the vial being opened without this being known.

With packages as above described, very con-

venient means is provided for making up samples of "unknowns" in considerable quantity at a central source and packaging these in a manner which maintains the integrity of the contents, provides the teacher with a ready at hand sample, the contents of which are known to him without analysis on his part, and which may be readily placed in the student's hands without bearing any indication as to what the substance or substances are which he is expected to find by his analysis. Greater variety of "unknowns" and greater accuracy of analysis is obtainable at a central source, than is ordinarily obtained by the individual teacher with the limited time at his disposal.

80 The invention may receive other embodiments than that herein specifically illustrated and described.

85 I claim:—

90 A label having a severable portion, and a line 95 of lock-stitched thread through the label arranged to be pulled to sever the label.
